FISH LURE

Henry Taylor, Suite B-106, 210 5th Ave.,
New York, N.Y.

Filed June 20, 1961, Ser. No. 65,651

Term of patent 14 years

(Cl. D31—4)

FIG. 1 is a plan view of a fish lure showing my new design;

FIG. 2 is a side elevational view;

FIG. 3 is an end view; and

FIG. 4 is an end view taken opposite that of FIG. 3. The broken lines shown in FIG. 1 are for illustrative purposes only.

I claim:

The ornamental design for a fish lure, as shown and described.
